UNITED STATES PATENT OFFICE.

KARL ALBERT WEBER, OF LOS ANGELES, CALIFORNIA, ASSIGNOR TO WEBER SHOW-CASE & FIXTURE COMPANY, OF LOS ANGELES, CALIFORNIA, A CORPORATION OF CALIFORNIA.

SODA FOUNTAIN.

Application filed September 8, 1925. Serial No. 54,945.

This invention relates to soda fountains constructed as compact fixtures for use in confectionery stores, drug stores and the like.

Soda fountains as now constructed have a limited capacity of ice cream storage due to the fact that the way in which such a soda fountain fixture may be constructed is limited by the reach of the operator, that is, a soda fountain must be of such a narrow width that the operator may easily reach the counter provided in the front thereof. This limiting of the width of the soda fountain, together with the fact that for practical reasons of space and design the length of the fountain is limited, makes the capacity of soda fountains very limited; that is, the number of ice cream containers of the customary design and size that can be stored in the cooling chambers provided in such soda fountains is extremely limited. Another serious defect of the compact design and construction of soda fountains is the extremely low cooling efficiency obtained in such a fixture as often, though the walls of the fixture are constructed of an insulated material, the edges of the ice cream containers must be adjacent these insulated edges or sides and each cooling container customarily has two such edges exposed to the greatest point of heat radiation into the cooling chamber.

An object of this invention is, therefore, to provide a soda fountain of increased storage capacity relative to the length and width of the fixture.

Another object of this invention is to provide a soda fountain fixture in which the cooling efficiency of the cooling chamber is increased.

Another object of this invention is to provide a soda fountain fixture in which the width of the fixture is decreased relative to the storage capacity so that the cabinet of the fixture may be made of increased height to more readily position the separate parts thereof in points of accessibility in relation to the operator of the soda fountain.

Another object of this invention is to provide means for distributing the handling of the syrup at the soda fountain so that the customary syrup containers will be eliminated from their customary position adjacent the inner edge of the counter.

Another object of this invention is to pro-

vide means whereby the syrup containers may be positioned at a point of accessibility away from the upper surface of the cabinet of the soda fountain.

Another object of this invention is to increase the capacity of syrup containers at the soda fountain and to eliminate waste and sloppage of the syrup.

Another object of this invention is to so position the syrup outlets in relation to the charged water outlet or outlet so that the operator serving at the fountain may serve with one hand.

Another object of this invention is to provide a means for disposing the syrup so that syrup containers as obtained from the producer may be employed directly without necessitating the changing of the syrup to separate containers so as to eliminate handling of the syrup.

Another object of this invention is to provide a soda fountain in which means are provided for the storage of glasses, cups and the like behind the counter of the fountain in a point of ready accessibility.

Other objects and advantages of this invention will be apparent from the following detailed description of a preferred embodiment thereof as illustrated in the accompanying drawings, in which drawings:

Fig. 1 is a perspective view of a soda fountain embodying this invention.

Fig. 2 diagram of connections embodied in this invention.

Fig. 3 is an end elevation of a soda fountain embodying this invention.

Fig. 4 is an enlarged sectional side elevation of a syrup container illustrating means for connecting the same to a pressure line.

In the preferred embodiment of this invention illustrated in the accompanying drawings, 1 illustrates a cabinet having insulated side walls 2 and a bottom 3 and having an insulated cover 4. Within the cabinet 1 containers 5 are supported for the storage of ice cream and other articles which it is desired to cool. 6 illustrates a cooling chamber in which a cooling medium is placed. The cooling medium employed may be either ice, brine or other cooling medium, as desired or preferred. 7 illustrates a partition member which, together with the forward partition member 8, supports the counter 9, which counter 9 preferably over-

hangs the partitions 7 and 8 at the front and rear sides, as illustrated at 10 and 11. 12 illustrates the customary carbonated water faucets which are connected with any suitable source of carbonated water or other adequate carbonating machine, while 13 illustrates a faucet which is connected with the water supply of the building.

Means are provided for dispensing the 10 syrups desired in the concocting or forming of the respective drinks, at the point of accessibility directly adjacent the faucets 12 and 13, which means comprise a plurality of faucets 14 which are connected through 15 separate pipes 15 to the syrup containers 16 which are, according to this invention, preferably situated below the sink 17 of the soda fountain. The syrup containers 16 are connected by means of pipes 18 to a pressure 20 pipe 19 which connects with a source of air pressure such as the air tank 20, which air tank may be maintained at the required pressure by any desirable or suitable form of automatic air pump (not shown), which 25 pump is connected with a pressure supply pipe 21 of the storage tank 20.

A gauge 22 is mounted on the storage tank 20 to permit the operator to ascertain whether or not the correct pressure is being 30 maintained therein. The syrup containers 16 within which the syrup is packed and supplied to the operator of the soda fountain so that it is unnecessary for the operator to transfer the syrup to auxiliary containers 35 having mechanical pumps therein, as has heretofore been the case. The removing of the syrup containers from the point immediately behind the counter 9 under the overhanging portion 10 thereof, as has heretofore 40 been the case, enables me to greatly increase the ice cream storage capacity of the cabinet 1 without increasing the width thereof, and has also enabled me to decrease slightly the width thereof, greatly to the 45 advantage of the operator, in that he is more easily enabled to reach the top of the counter 9, and by decreasing the width of the cabinet 1 I have been enabled to increase the height thereof to raise the containers 5 to a 50 point of greater accessibility in relation to the operator of the soda fountain.

I have discovered that in order to obtain the desired flow of syrup from the faucets 14, particularly the heavier syrups such as 55 chocolate and the like, requires the maintaining of from five to fifteen pounds pressure within the container 20, five pounds pressure being sufficient to deliver the heaviest syrup when only one of the faucets 14 is being operated to vent the pressure; however, I employ between ten and fifteen pounds pressure between the containers 16 so that at all times there will be sufficient 60 pressure to discharge the heaviest syrups 65 through the faucets 14. The putting of

the syrup containers 16 under pressure and discharging the syrups through the faucets 14 enables me to effectively eliminate all dripping commonly incident to the type of syrup dispensers now employed, in that 70 when the faucets 14 are connected to a common source of pressure 20, the closing of the faucets exerts a suck-back on the syrup due to the change in pressure created in the remaining containers 16 and the storage 75 tank 20. This greatly saves the syrup being used and eliminates the necessity of the operator having to clean and scour the upper surface of the cabinet at such frequent intervals.

80 The pipes 18 and 15 are connected with the syrup container 16 through stoppers 23, which are formed with two holes 24 and 25 therein for the insertion of the end of the pipes 15 and 18 therethrough. The lower 85 end of the pipe 18 terminates directly below the lower end of the stopper 23 so that the pressure from the tank 20 is imparted to the surface of the syrup within the container. The pipe 15 terminates at the lowest 90 end of the container 16 so that approximately all of the syrup will be discharged from the containers 16 through the pipes 15 to the faucet 14.

In order to provide storage space for glass 95 cups, ice cream dishes and the like, behind the soda fountain at a point of ready accessibility in relation to the operator of the fountain, I provide a shelf 26 located preferably above the faucets 14 and under the 100 projecting portion 10 of the counter 9, upon which glasses 27, cups 28 or dishes 29 may be positioned.

The putting of the syrup containers 16 under the sink 17 away from the upper surface of the cabinet 1 enables me to employ two ice-cream containers back to back, as illustrated in Figs. 1 and 4, at a point of ready accessibility in relation to the operator without decreasing the cooling efficiency 110 of the cooling medium employed within the chamber 6. The covers 4 for these containers 5 are at all times easily removed without interference from other parts of the fixture, and the containers 5 are also so situated as 115 to at all times enable the operator of the soda fountain to reach the contents thereof.

The employing of the two ice-cream containers back to back enables me to increase the cooling efficiency of the medium employed within the chamber 6, as it enables me to mount a greater number of containers 5 in a given space than where it is necessary, because of the width of the cabinet 1, to install such containers 5 in straight lines, as 125 it enables me to decrease the exterior radiating surface of the cooling chamber 6 in relation to the number of containers 5 which may be supported therein.

Having fully described a preferred em- 130

bodiment of this invention, it is to be understood that I do not wish to be limited to the exact details of construction and operation herein set forth, which may obviously be varied in detail without departing from the spirit of the invention, as set forth in the appended claim.

I claim:

The combination of a soda fountain including a cabinet having insulated walls and bottom and containing a plurality of food containers positioned in transverse rows, a counter in front of and extending laterally beyond said containers, a sink back 15 of said counter, a plurality of syrup con-

tainers thereunder, a pressure storage tank containing gas under pressure, a conduit connecting said storage tank with each of said syrup containers, syrup discharge pipes extending to near the bottom of each container, means for releasably securing a separate container connecting means to each container in fluid-tight relation, and a valve in each syrup discharge pipe, said valves being arranged to the rear of said counter, 20 and adjacent to the openings to said food containers.

Signed at Los Angeles, Calif., this 27 day of August, 1925.

KARL ALBERT WEBER.
